CLAIM

The ornamental design for a brake noise insulator shim, as shown and described.

DESCRIPTION

FIG. 1 is a perspective view of a brake noise insulator shim showing our new design;

FIG. 2 is a front elevation view thereof;

FIG. 3 is a right end elevation view thereof;

FIG. 4 is a left end elevation view thereof;

FIG. 5 is a top plan view thereof;

FIG. 6 is a bottom plan view thereof; and,

FIG. 7 is rear elevation view thereof.

The broken lines shown throughout the drawing figures are for illustrative purposes only and form no part of the claimed design.
